Int. Cl. D26—05

U.S. Cl. D48—16 A

Fig. 1

Fig. 2

FIG. 1 is a front perspective view of a color display screen showing my new design, the rear face being a mirror image of the front face.

FIG. 2 is an enlarged cross-sectional view thereof taken on line II—II of FIG. 1, the view being broken away for purposes of illustration.

The color display screen is shaded to indicate contrast.
I claim:

The ornamental design for a color display screen, substantially as shown and described.
